US00D608679S

(12) **United States Design Patent**
Jouan

(10) **Patent No.:** **US D608,679 S**
(45) **Date of Patent:** **** Jan. 26, 2010**

(54) **PENDANT**

(75) Inventor: **Aurélie Jouan**, Billancourt (FR)

(73) Assignee: **Swarovski Aktiengesellschaft**, Triesen (LI)

(**) Term: **14 Years**

(21) Appl. No.: **29/342,649**

(22) Filed: **Aug. 28, 2009**

Related U.S. Application Data

(62) Division of application No. 29/311,009, filed on Dec. 5, 2008.

(51) **LOC (9) Cl.** **11-01**

(52) **U.S. Cl.** **D11/83**

(58) **Field of Classification Search** ..... D11/1-7, D11/9, 13-14, 16-17, 26, 40-44, 46, 48-49, D11/53, 55-57, 61, 66, 69, 74-77, 79, 80-92, D11/95-103, 105, 108, 116, 128; 63/1.11, 63/1.16, 3, 13, 14.1, 15, 15.1-15.4, 26-28, 63/32-33, DIG. 3; D21/594-595, 621, 622, D21/630-631, 658-659

(57) **CLAIM**

The ornamental design for an pendant, as shown and described.

DESCRIPTION

FIG. 1 is a front view of the invention;

FIG. 2 is a rear view of the invention;

FIG. 3 is a left side view of the invention;

FIG. 4 is a right side view of the invention;

FIG. 5 is a bottom view of the invention; and,

FIG. 6 is a top view of the invention.

The broken lines illustrate portions of the pendant which form no part of the claimed design.
